UNITED STATES PATENT OFFICE.

GEORGE W. KIRCHHOFFER, OF NEW YORK, N. Y.

BRACKET.

SPECIFICATION forming part of Letters Patent No. 622,370, dated April 4, 1899.

Application filed November 16, 1898. Serial No. 696,597. (No model.)

To all whom it may concern:

Be it known that I, GEORGE W. KIRCHHOFFER, a resident of the borough of Manhattan, city, county, and State of New York, have invented certain new and useful Improvements in Brackets, of which the following is a specification.

My invention relates to brackets for suspending bird-cages or hanging baskets and the like upon a wall without marring the same.

In the accompanying drawings I have shown a bracket embodying my invention, together with its application to a wall.

15 In the said drawings, Figure 1 is a side view of the bracket, showing the same in position on a wall; and Fig. 2 is a rear view of the supporting device forming part thereof.

In the drawings, *a* is the base of the bracket, which is preferably in the form of a plate and likewise preferably provided with at least three points for application to a wall, *b*, *c*, and *d*. A rod or other projection *e* extends from the base. The base and rod constitute a sup-

25 porting device for a bird-cage or other object. At or near the end of the rod or projection is secured one end of a suspension device, in the form of a string, cord, or wire *f*, which preferably passes through a ring *g*, with a hook *h*

30 to take over a molding *i* on a wall *A*, and is secured at its other end to the rod *e* or base

a, thus constituting a bifilar suspension. The rod *e* may likewise be provided with a hanger *j*, which is preferably in the form of a hook adjustable along the rod *e*.

35 In using the bracket the base *a* is placed against the wall without being secured thereto, and the hook *h* is engaged over the molding *i*, the bracket being thereby suspended and pressed against the wall by its own weight 40 or the weight of a bird-cage or other article *B*.

It will of course be understood that the details of construction may be departed from without departing from the spirit of my invention.

45 What I claim, and desire to secure by Letters Patent, is—

The combination of a supporting device comprising a base resting against a wall but unattached thereto and a projection from 50 said base, and a continuous bifilar suspension device secured to the projection at a point remote from said wall and to a point of the supporting device near said wall and passing through a ring or other support above the 35 said supporting device so that the device will be self-adjusting, substantially as described and for the purposes set forth.

GEORGE W. KIRCHHOFFER.
